UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

TACKING AND STITCHING MACHINE.

1,164,789.

Specification of Letters Patent. Patented Dec. 21, 1915.

Application filed September 6, 1912. Serial No. 718,807.

To all whom it may concern:

Be it known that I, ALBERT H. DE VOE, a citizen of the United States, residing at Westfield, in the county of Union and State of New Jersey, have invented certain new and useful Improvements in Tacking and Stitching Machines, of which the following is a specification, reference being had therein to the accompanying drawings.

10 This invention has for its primary object to provide a mechanism for applying to one of the flaps of a cloth shoe-upper one or more cord-loops to receive a fastening member applied to the other flap of the shoe-upper. 15 In the class of Japanese shoes known as "tabis," it is customary to apply to one of the heel-flaps a cord which is doubled at the upper edge of the flap and led downwardly in two parallel branches extending 20 through and alternately on the outer and inner faces to provide on the outer face spaced parallel cord-loops between which and the face of the flap the flat metallic tongues of fasteners secured to the inner face of the 25 other flap are inserted.

The invention has for its further object the embodiment in a sewing machine of special features for its adaptation for this and other classes of work.

30 In its preferred embodiment, the present improvement comprises stitch-forming mechanism including two reciprocating and reciprocally jogging needles with correspondingly jogging loop-takers and controlling means whereby the jogging movements are periodically produced and interrupted for the production of spaced groups of tacking stitches connected by series of straightaway stitches. A controlling cam adapted to be 35 uncoupled from its driving means after performing a predetermined number of tack-forming cycles is employed to effect the periodical jogging movements of the stitch-forming mechanism, to produce the close 40 spacing of the component stitches of the initial tack, to control the number of intermediate straightaway stitches, and to regulate the spacing of the component stitches of the succeeding tack or tacks. A counting device 45 is preferably employed to determine the number of turns of the controlling cam, and hence the number of tacks in a complete stitching cycle.

Each tack is preferably composed of alternate single-step and two-step overseam

stitches, the former embracing and the latter passing through the cord, so as to not only bind the cord firmly to the fabric but to secure it against endwise displacement thereon; and the straightaway stitches are 60 formed in alinement with one edge of the tack and therefore at one side of the cord so as to avoid leaving any loose thread-ends at the intermediate tacks and to provide unstitched portions of cord intermediate the 65 tacks for engagement of the fasteners.

The invention will be understood in its details of construction by reference to the accompanying drawings, in which—

Figure 1 is a front side elevation of a 70 two-needle sewing machine embodying the improvement and Fig. 2 a plan of the same with the bracket-arm removed and the bed-plate slides retracted to expose the loop-taker mechanism. Fig. 3 is a rear side elevation and Fig. 4 an under-side view of the machine. Figs. 5 and 6 are transverse sections showing portions of the feeding mechanism. Fig. 7 is a front end view of the bed-plate and parts beneath, and Fig. 8 a 75 transverse section of the entire machine, upon a larger scale, showing the controlling cam with its actuating devices and parts controlled thereby. Fig. 9 is a sectional elevation of the needle-bar and a part of its 80 operating means, and Fig. 10 a plan of a portion thereof. Figs. 11 and 12 are plan views of the needle-clamp, Fig. 13 a perspective view of one of the needle-carriers, Fig. 14 a perspective view of a detail of the 85 needle-jogging means, and Fig. 15 an end view of the needle-clamp. Fig. 16 is a plan of the controlling cam and a portion of its 90 actuating means. Fig. 17 is a plan of the cycle counting mechanism and Fig. 18 an 95 end view of a portion of the same partly in section. Figs. 19 and 20 are perspective views of the presser-foot viewed from above and below the same. Figs. 21, 22 and 23 are perspective views showing details of the 100 counting device. Fig. 24 is a face view of a portion of the tabi heel-flap provided with cord-loops applied in accordance with the present invention.

The machine shown in the drawings is of 105 the type represented in the United States patent to Charles F. Gray, No. 821,587, dated May 22, 1906, and comprises a frame constructed with the bed-plate 1 and bracket-arm composed of the hollow standard 2 and 110

overhanging tubular arm 3 in which latter is journaled the main-shaft 4 carrying at its rearward end the balance-wheel 5 with belt-pulley 6.

5 Journaled in the head of the bracket-arm is the tubular needle-bar 7 upon the upper end of which is secured by clamp-screws 8 the split-collar 9 carrying the lateral pin 10 which is embraced by the apertured lower 10 end of the pitman 11 whose apertured opposite end embraces the usual crank-pin 12 of the take-up cam-cylinder 13 fixed upon the main-shaft 4. At its lower end the needle-bar 7 is formed with lateral flanges 14 whose 15 opposite edges are fitted between the side-walls of the transversely channelled head 15 secured thereto by means of the transverse screws 16. Fitted within the channel of the head 15 are the reciprocally sliding needle-carrying blocks 17 each provided at one end with a reduced portion 17' interposed between the body portion of the other block and the adjacent wall of the channel, as represented more particularly in Figs. 12 and 20 25 13, and each provided near the center of its length with a needle-socket in which the shank of a needle 18 is secured by means of the set-screw 19. To an extremity of each block 17 is secured by a screw 20 a bent arm 20 25 30 35 40 45 50 55 60 65 70 75 80 85 90 95 100 105 110 115 120 125 130 having an offset portion provided with a thread-guiding aperture 22 arranged in advance of its respective needle.

Near the larger end of each block 17 is formed a vertical aperture 23 entered by the depending fulerum-pin 24 of a link 25 having at its opposite end the upwardly projecting pin 26 entering one of two diametrically opposite apertures in the flange 27 which is housed in a recess in the lower end 40 45 50 55 60 65 70 75 80 85 90 95 100 105 110 115 120 125 130 of the needle-bar 7 and is formed upon the lower end of the rod 28 extending upwardly through the needle-bar.

The collar 9 is formed with an upward extension 9' in which is journaled the lower portion of a tubular rod 29 to the lower end of which latter is applied through a lateral opening between the parts 9 and 9' of the collar an intermediate collar 30 through threaded apertures in which the rod 29 is inserted the set-screw 31 by which they are secured to the inner rod 28 whose upper end enters the lower portion of the rod 29, as represented in Fig. 9.

The tubular rod 29 is journaled in a bushing 32 in the head of the bracket-arm which is embraced by the spaced members 33 and 34 of a rocking bracket 35 journaled upon the rod 29 and whose lower member has a radial slit in which is secured by the screw 36 the spline 37 entering a longitudinal key-way 38 of the rod 29. The upper member 33 of the bracket 35 carries a ball-stud 39 which is embraced by a strap 40 at one end of a pitman 41 whose opposite end carries a strap 42 embracing a stud 43 adjust-

ably secured by means of the clamp-nut 44 within a slot 45 of the arm 46 of an angle-lever fulerummed at 47 upon the bracket-arm and having a second arm 48 connected with the pitman 49 extending downwardly 70 through the aperture 50 of the standard 2 and the bed-plate.

The lower end of the pitman 49 is pivotally connected with a lateral arm 51 of a rocking frame 52 which is journaled upon 75 the feed rock-shaft 53 sustained beneath the bed-plate. The frame 52 has a second lateral arm 54 carrying a roller-stud 55 which enters a peripheral groove 56 of the controlling cam-wheel 57. The rotation of the 80 cam-wheel 57 by means to be described imparts rocking movements to the frame 52 which are transmitted through the described connections to the rod 28 whose crank-and-pitman connections with the needle-carrying block 17 cause them to move reciprocally transversely to the direction of reciprocation of the needle-bar imparted by the link connection 11 with the crank pin 12 carried by the main-shaft.

The main shaft 4 is provided with the usual quartering cranks 58 embraced by straps at the upper ends of the pitmen 59 whose lower ends are similarly provided with straps embracing the quartering cranks 60 of the lower shaft 61 journaled beneath the bed-plate. The shaft 61 has secured thereon the gear-wheel 62 meshing with the pinion 63 fixed upon the intermediate shaft 64 which is journaled in the bearing members 65 depending from the bed-plate and carries the bevel pinion 66 meshing in turn with the bevel pinion 67 which is shown formed integral with the intermediate gear 68 mounted upon the stud 69 supported beneath the bed-plate.

Adjustably secured upon seats provided therefor upon the under side of the bed-plate by means of screws 70 passing through slots 71 therein are the feet 72 of brackets 73 formed with spaced and alined parallel bearing bosses 74. Journaled in each pair of alined bearing bosses are the fulcrum-pins 75 upon which are secured by means of set-screws 76 the spaced bosses 77 of a joggling frame formed with an upwardly extending bearing member 78 and a lateral arm 79 terminating in an apertured transverse boss 80. In each of the bearing members 78 is journaled the vertical loop-taker shaft 81 having secured upon its lower end a pinion 82 meshing with the intermediate gear 68 and having upon its opposite end the loop-taker 83 formed with the loop-seizing beak 84 adapted to coöperate respectively with the needles 18 and having journaled therein the stationary thread-case 85 provided with the usual rotation-restraining means and containing the lower thread-bobbins 86.

The lateral arms 79 of the jogging frames extend in opposite directions and the boss 80 of each has slidably fitted therein one end of a pivotal pin 87 whose opposite end is secured by a set-screw 88 in a transverse aperture at the lower end of a link 89. Each link 89 has at its upper end a second transverse aperture disposed at right angles with that at the lower end in which is secured a pivotal pin 90.

One of the pins 90 is slidably fitted within an aperture in the laterally and forwardly extending crank-arm 91 of the rocking frame 52 while the other pin 90 is similarly fitted within an aperture formed in the lateral extension 92 of the frame 52 and in alignment with the aperture of the arm 91. The links 89 and pins 87 and 90 thus form a universal-joint connection between one of the bracket-arms 79 and the frame members 91 and 92, respectively, and serve to transmit to the loop-takers reciprocal lateral jogging movements corresponding with those of the respective needles. In practice, the axes of the fulcrum-pins 75 pass through the intermeshing points of the gears 68 and 82, so that the lateral movements of the loop-taker shafts do not materially affect the operative relation between the driving and driven gears.

Secured upon the lower shaft 61 is a worm 93 meshing with the worm-wheel 94 which is shown formed integral with the sleeve 95 journaled upon the fixed tubular vertical bearing stud 96 and carrying the coupling disk 97 provided with the annular series of uniformly spaced apertures 98. Within the bearing stud 96 is journaled the tubular hub 99 of a disk 100 formed in its lower face with a radial channel 101 within which is fitted the rigid arm 102 secured to the shoudered lower end of the coupling rod 103 to which it is fastened by means of the nut 104.

The rod 103 is extended upwardly through the hub 99 of the disk 100 and has fixed upon its upper end above the bed-plate the thrust-collar 105. The arm 102 has extending from its upper face the coupling stud 106 whose reduced upper portion 107 is adapted to enter one of the apertures 98 of the disk 97, but which is normally disengaged from such disk by the action of a spring 108 interposed between a washer 109 resting upon the top of the arm 102 and the upper end of a socket 110 formed therefor around the rod 103 in the hub 99 of the disk 100.

Tapped into threaded apertures 111 in the lower face of the annular flange 57 of the cam-wheel 57 are the screws 112 which secure the cam-wheel to the upper face of the disk 100. When the cam is coupled to the worm-driven and constantly running disk 97, as represented in Fig. 8, it causes the intermittent rocking of the frame 52 which

causes the reciprocal jogging of the needles and their respective loop-takers in the production of parallel lines of straight-away and zigzag stitching.

The shaft 61 is shown provided with the feed-actuating cam or eccentric 113 upon the upper side of which rests the flat operative face 114 of a lateral arm 115 fixed upon the rocking sleeve 116 which is journaled upon the rock-shaft 117 mounted in the bearing members 118 depending from the bed-plate. The rock-shaft 117 has fixed upon its rearward end the depending and laterally extending arm 119 having a wearing face 120 adapted for engagement with the opposite side of the cam 113 from the arm 115. The arms 115 and 119 are normally pressed together by means of a spring 121 embracing the sleeve 116 and having one extremity secured to a collar 122 fixed upon said sleeve 85 and the other end attached to a collar 123 secured upon the rock-shaft 117.

The arm 119 is shown provided in its rearward face with a segmental channel 124 in which is fitted the slide-block 125 having pivotally connected therewith one end of the bent link 126 whose apertured opposite end is connected by means of the screw-pin 127 with the upwardly extending arm 128 secured upon the feed rock-shaft 53. The sliding connection between the arm 119 and the link 126 is shifted toward and from the rock-shaft 117 by means of a link 129 pivotally connected by the pin 130' to the link 126 at its lower end and attached at its upper end to the lateral arm 130 of the feed-regulator rock-shaft 131 journaled in and transversely of the standard 2 and having fixed to its rearward end the finger-lever 132.

Near its forward end the feed rock-shaft 53 has secured thereon the crank-arm 133 carrying the stud-screw 134 which enters an apertured extremity of the feed-bar 135 to which is secured the usual feed-dog 136. The opposite end of the feed-bar is formed with the fork 137 which is in practice entered by a slide-block carried by the stud 138 which is sustained by the lateral arm 139 upon the forward end of the feed-lift rock-shaft 140 to whose rearward end is secured the hub 141 of a laterally extending arm 142 adapted to rest upon the feed-lift cam or eccentric 143 fixed upon the lower shaft 61. The hub 141 is provided in the top at one side of the rock-shaft 140 with a socket between the bottom of which and the under side of the bed-plate 1 is inserted a spring 144 which normally presses the arm 142 downwardly into operative relation with the lifting cam 143.

The feed-actuating arm 119 is formed at its outer extremity with a lateral seat 119' to which is secured by means of the screw 145 the base of an arm 146 formed with a transverse socket 147 in which is journaled

the slide-pin 148 carrying at its outer end the roller-stud 149. The enlarged rearward end or head 150 of the pin 148 is pressed backwardly by means of a spring 151 interposed between the same and the inner end of the socket so as to maintain the roller-stud 149 normally retracted into operative relation with the outer cam-track 152 upon the lower face of the cam-wheel 57. In its inner or extended position, the roller-stud 149 is adapted for engagement with the inner inclined segmental cam-track 153 of the cam-wheel.

The cam-tracks 152 and 153 are so related to the arm 146 and roller-stud 149 that they serve as stops in the rotation of the cam-wheel acting in opposition to the spring 121 to prevent the continuous engagement of the arm 119 with the actuating cam 113, the cam-track 152 permitting engagement only at the high point of the cam 113 with the wearing face 120, while the cam-track 153 wholly prevents such engagement while serving by its inclination to permit a slight continuous movement of the arm 119 toward the cam 113 under the action of the spring 121. As will be observed, the spring 121 serves to normally draw together the arms 115 and 119 of the yielding yoke so as to lightly embrace the cam 113, the spacing apart of the wearing faces 114 and 120 being determined by the adjusting screw 154 carried by the tail 115' of the arm 115, and whose point rests against the extension 119" of the arm 119, as represented in Fig. 6.

As represented more particularly in Figs. 4 and 8 of the drawings, a segmental gap 155 is formed in one side of the cam-wheel to afford clearance for the roller-stud 149 so as to permit the free vibration of the arm 146 under the action of the actuating cam 113 upon the arm 119 during a portion of the rotation of the controlling cam, thereby permitting the feed-dog to receive a movement corresponding to the full throw off the feed-actuating cam in the production of a portion of the stitches of a sewing cycle. A portion of the outer cam-track 152 is also cut out for reception of the adjustable channeled section 156 which is secured to the cam by means of fastening screws 157 passing through inclined slots 158 in the section 156. By loosening the screws 157, the section 156 may be shifted upwardly or downwardly in its recess so as to change its controlling position relative to the roller-stud 149.

Suitably journaled beneath the bed-plate is an endwise movable stop-rod 159 whose forward end extends, in the initial position of the parts, beneath the lower edge of the striking plate 160 secured by screws 161 upon the feed-lift arm 142, as represented in Fig. 5, so as to maintain the feed-dog in elevated position and out of the range of movement

of the lifting cam 143 while the roller-stud 149 performs its slow and continuous work-advancing movement under the control of the cam-track 153. The rod 159 has fixed thereon the hub 162 of a depending arm 163 having a flat operative forward face adapted to contact with the head 150 of the pin 148 to shift the roller-stud 149 forwardly under the action of a spring 164 surrounding the rod 159 and interposed between the 75 hub 162 and the upper end of which is rigidly secured the segmental arm 167 carrying the roller-stud 168 adapted for engagement with the peripheral projection 169 of a cam-disk 170 fixed upon the upper end of the tubular hub 99 of the coupling disk 100.

The arm 167 is provided adjacent the roller-stud 168 with a forwardly extending finger-piece 171 and at the opposite end with a tooth 172 adapted for engagement with a detaining shoulder afforded by the collar 173 upon the lateral arm 174 of a latch-lever fulcrumed upon the push-rod 175 which is journaled in the bracket-piece 176 secured to the standard 2 and extends downwardly through an aperture in the 95 bed-plate 1. The latch-lever is formed with a rearwardly extending arm 177 carrying the tripping pin 178 and normally pressed to bring the arm 174 into latching relation with the arm 167 by means of a spring 179 100 interposed between the same and the base of the standard 2. The hub 177' of the latch-lever extends from the lower side thereof and rests upon the top of the bed-plate in contact with which it is maintained by 105 means of the rod 180 secured in the lug 181 of the latch-lever and having its upper end extended beneath the bracket-piece 176.

To the push-rod 175 below the bracket-piece 176 is secured by means of the set-screw 182 the hub 183 of a plural-armed member comprising the coupling controlling arm 184 having secured upon a seat in its outer end by means of the screw 185 the wearing plate 186 adapted for introduction 110 beneath the thrust-collar 105 of the coupler rod 103. Extending rearwardly from the hub 183 is an arm 187 having a fork 188 in its extremity which embraces a tripping rod 189 slidingly mounted in the bearing member 190 formed upon an arm having a split collar 191 clamped by means of the screw 192 upon the oscillatory rack-bar 193 which is journaled in the bearing members 194 of the bracket 195 secured by screws 196 upon 125 the bed-plate 1 at the foot of the standard 2.

The rack-bar 193 has near the top of its forward extremity a series of nicks 197 adapted to be entered by the inturned lip 198 of a flat spring 199 secured by means

a screw 200 to a seat formed upon the top of a rigid arm 201 having a split boss 202 clamped upon the tripping rod 189 and formed at its free end with the fork 203 embracing the rod 189 and formed with the slit 204 to receive the lip 198 of the spring, which latter is provided at its free end with the button 205 for retracting the lip 198 from one of the notches 197 in order to shift the rod 189 relatively to the bar 193. The spring 199 is formed with an in-turned stop-flange 206 adapted to engage the upper member of the fork 203 to limit the retractive movement of the spring.

15 The bar 193 is surrounded by a spring 207 which is interposed between the rearward bearing member 194 and the collar 208 fixed thereon, and acting to normally press the bar 193 into extreme forward position with the collar 208 in contact with the forward bearing member 194, as represented in Fig. 2. Formed in the front side of the bar 193 is a series of ratchet-teeth 209 (Figs. 17 and 18) extending forwardly over which is a pawl-retracting flange 210. In normal engagement with the ratchet-teeth 209 is the holding pawl 211 fulcrumed upon a screw-pin 212 tapped into the bed-plate and an actuating pawl 213 fulcrumed upon the screw-pin 214 on the reduced forward end of the rearwardly extending arm 215 of a rock-lever mounted upon the fulcrum-stud 216 tapped into the bed-plate and having a forwardly extending arm 217 formed with a yoke 218 which embraces a cam or eccentric 219 fixed upon the tubular hub 99 of the coupling disk 100. The tail 213' of the pawl 213 is formed in the rearward edge with a socket to receive a spring 220 resting against the adjacent edge of the holding pawl 211, whereby both pawls are maintained normally in operative relation with the ratchet-teeth 209.

As will be observed, for each rotation of the controlling cam-wheel 57 the rock-lever 215 217 receives one rocking movement, and the counting bar 193 receives a step backwardly, carrying with it the tripping rod 189. The rod 189 is provided with a transverse tripping pin 221 which thus receives step-by-step movements toward the forked extremity 188 of the arm 187 and at the end of a predetermined number of rotations of the controlling cam engages the forked extremity of the tripping arm 187, thereby shifting the plural-armed member 183 184 187 in opposition to the torsional action of the spring 222 whose opposite ends are attached respectively to the collar 223 fixed to the push-rod 175 and the bracket-piece 176, thereby retracting the wearing plate 186 from beneath the thrust-collar 105 and permitting the coupling rod 103 to descend under the action of its spring 108, thus uncoupling the controlling cam from the con-

tinuously driven disk 97. As the spring 222 is substantially stronger than the spring 108, it will be seen that the former acts to maintain the push-rod 175 in raised position with its stop-collar 224 in engagement with the under side of the bracket-piece 176 and the spring 108 compressed to hold the coupling stud 106 in operative engagement with the disk 97.

The bracket-arm member 3 sustains the usual fulcrum-stud 225 upon which is mounted the presser-bar lifting rock-lever 226 to the rearward arm of which is connected by means of the screw-pin 227 the apertured head 228 of the treadle-rod 229 passing through the usual aperture in the bed-plate beneath which it is formed with the hooked extremity 230 to receive the upper end of the chain 231 whose opposite end is in practice connected with an actuating treadle. The treadle-rod has secured thereon near its upper end by means of set-screws 232 the hub 233 of a laterally extending rigid arm 234 extending above the top of the push-rod 175, and it is also provided slightly above the bed-plate with a fixed collar 235 having in its lower face an upwardly and rearwardly inclined cam-face 236 adapted for engagement with the tripping finger 178 of the latch-lever 174 177, (Fig. 3).

In order to set the machine for a tacking and stitching operation, the treadle-rod 229 is drawn down to lift the presser-foot above the throat-plate 237 for introduction of the work, which causes the engagement of the collar 235 with the tripping finger 178, thus disengaging the collar 173 from the tooth 172 of the arm 167, which causes the stop-rod 159 to advance under the action of its spring to bring its forward extremity beneath the member 160 of the feed-lift bar 142 and simultaneously press the pin 148 forwardly to shift the roller-stud beneath the upper portion of the inclined cam-track 153. At the same time, the depression of the tripping rod 189 under the action of the fork 188 causes the rocking of the counting bar 193 into the full line position represented in Fig. 18, wherein the flange 210 engages the pins 211' and 213'' upon the holding and actuating pawls 211 and 213 to forcibly retract the latter from the ratchet-teeth 209, thereby permitting the counting bar 193 to move into extreme forward initial position under the action of its spring 207, as represented in Fig. 2. The depression of the arm 184 with the push-rod 175 causes the descent of the wearing plate 186 from the side of the thrust-collar 105 below the latter beneath which it is caused to move under the torsional action of the spring 222, and the release of the treadle-rod 229 thereafter permits the push-rod 175 to rise under the action of the spring 222 and with it to rock the counting bar 193 into initial posi-

tion (represented in dotted lines in Fig. 18) and to lift the coupling rod 103 for coupling the disk 100 and the attached cam-wheel 57 with the coupling disk 97.

- 5 As will be seen by reference to the accompanying drawings, the peripheral groove of the controlling cam is formed with a straight portion 56 followed by a full step 56' downward and two half-steps 56² and 56³ upward, 10 the series being repeated throughout the remainder of the circumference. As shown herein, the cam is designed to impart to the rocking frame 52 a succession of 18 jogging movements in groups of three, one movement downward followed by two upward 15 movements of one-half the amplitude of the initial movement. By this means, the stitch-forming mechanism receives a jog in one direction followed by a two-stage jog in the opposite direction, so that the needle puncture for the second of each group of three 20 stitches is disposed in a line intermediate the first and third punctures.

As herein shown, the transversely slotted lower portion of the presser-bar 238 has secured therein by means of the fastening screw 239 the presser-foot shank 240 having rigidly connected therewith the foot-plate 241 formed with the transversely spaced 25 needle-apertures 242 separated by the forwardly extending tongue 243. Secured upon the forward end of the foot-plate by screws 244 is a flat spring 245 carrying the depending laterally spaced cord-detaining 30 prongs or spurs 246 passing downwardly through a slot in advance of the tongue 243, such prongs being disposed in front of the needle-apertures 242.

The foot-plate is provided intermediate 35 its upturned forward extremity and the needle-apertures 42 with the lateral notches 247 through which the cord-loop is led from above the forward portion of the foot-plate and through the laterally spaced longitudinal 40 guide-grooves 248 in the bottom of the foot-plate, around the depending prongs 246, as represented in Figs. 19 and 20. Rearward of the needle-holes and in register 45 with both of the grooves 248 in the bottom of the foot-plate is the clearance channel 249 through which the doubled cord is adapted to pass as the stitching and feeding progresses.

As represented in Fig. 19, the foot-plate 50 has secured thereon rearward of the needle-apertures by means of the screw 250 the transversely disposed plates 251 having formed near one edge the V-shaped notch 252 with a sharp cutting edge and affording 55 an adjacent downturned thread-nipping lip 253 to provide for the convenient severing and nipping of the needle-threads at the completion of a stitching operation.

In the application of cord-loops, as previously described, to the heel-flap of a tabi,

the treadle-rod 229 is first depressed to raise the presser-foot and the fabric *m* is introduced under the latter with the upper edge *m'* of the flap slightly in advance of the needle-apertures, and the cord *c* is then introduced beneath the presser-foot and a loop *c'* thereof caught upon the rearward faces of the prongs 246 from which it is drawn forwardly into the grooves 248 and then upwardly through the notches 247 from which the two limbs of the loop are led forwardly as represented in Fig. 19. The presser-foot is then lowered by release of the treadle-rod, the several parts of the mechanism having been set in initial stitching position by actuation of the presser-foot lifter as previously described.

The setting of the machine in operation causes the production of an initial group of 18 closely spaced tacking stitches *s s'*, the longer stitches *s* embracing the cord adjacent the loop *c* and the shorter stitches *s'* embracing opposite sides of the cord and passing through the center thereof as represented at the left in Fig. 24. During the formation of these stitches, the stop-rod 159 sustains the feed-bar, as represented in Fig. 5, to maintain the feed-dog 136 constantly in engagement with the fabric *m*, and the feed-actuating arm 119 is maintained continuously out of operative relation with the cam 113, but is caused to advance uniformly toward the same by action of the spring 121 and the roller-stud 149 resting upon the inclined cam-track 153.

Just as the stud 149 reaches the end of the cam-track 153 and enters the clearance space 155, the nose or projection 169 of the cam 170 engages the roller-stud 168 of the arm 167 and thereby retracts the stop-rod 159 to disengage it from the feed-lifting arm 142, simultaneously retracting the arm 163 to enable the roller-stud 149 to retreat into the range of action of the cam-track 152. The arm 167 being held in retracted position by engagement with the latch-lever arm 174, the stitching proceeds with the roller-stud 55 in the straight portion of the cam-groove 56 and the feed-actuating arm in full engagement with the cam 113, thereby producing the six straightaway stitches *s''* extending along the inner sides of the cord *c*.

At the beginning of the second rotation of the controlling cam the cam-track 152 enters the range of vibratory movement of the roller-stud 149 under the action of the cam 113 upon the arm 119 (Fig. 6) and acts thereon as a stop to reduce the normal throw of the same, thereby shortening the feed-stroke to produce the first six initial stitches 125 *s s'* of the second tack which are somewhat more widely spaced than those of the first tack. The encounter by the stud 149 of the adjustable cam-track section 156 now permits a somewhat greater amplitude of move- 130

- ment of the arm 119, whereby the spacing of a second series of six stitches is somewhat increased, while the presentation of a final segment of the cam-track 152 similar 5 to the first causes the production of a third series of six stitches similar to those first formed, after which a series of six straightaway stitches is formed under the conditions previously described.
- 10 It will be observed that the rod 49 constitutes a normally inactive operative element connected with the needle-jogging angle-lever to which is imparted periodical active movements through its connection 15 with the controlling cam; the movements communicated to the needles through said element being at certain times of a two-stage character in the production of the zigzag or overseam stitches s' and at other 20 times of a single stage character as in the production of the stitches s , the needles thus having jogging movements of consecutively different amplitudes in the production of the zigzag or tacking stitches.
- 25 The tacking and straightaway stitching cycle last described is repeated a number of times for which the counting device is adjusted, beginning with the initial notch 197, each notch of the rod 193 representing a 30 rotation of the controlling cam, the position of the trip-rod 189 determining the number of rocking movements of the pawl-carrying arm 215 to effect the tripping of the arm 187 by the pin 221. As before explained, 35 the shifting of the arm 187 causes the lateral movement of the arm 184 to disengage the wearing plate 186 from the thrust-collar 105, thereby permitting the coupling rod 108 to descend under the action of its spring 40 108 for uncoupling the controlling cam 57 from the coupling disk 97. As this uncoupling takes place while the stop-rod 159 is retracted and the roller-stud 149 is in register with the clearance gap 155 of the cam 57, it will be seen that the continued 45 operation of the machine will now produce an indefinite succession of parallel straightaway stitches, the stitch-forming and feeding mechanisms acting under such conditions precisely the same as in any ordinary 50 straightaway stitching machine.
- It will be observed that the adjustment 55 upward or downward of the cam-track section 156 will effect a lengthening or shortening of each of the tacks after the first, by increasing or decreasing the spacing apart of the intermediate group of six stitches of such tack. It is also evident that, in case it is desired to produce a succession of tacks 60 composed of crowded tacking stitches, the manual shifting of the latch-lever 174 177 by means of the finger-piece 174' during the production of straightaway stitching succeeding an initial tack will permit the stop- 65 rod 159 to reassume initial position, so as to

restore the controlling mechanism to starting condition but without affecting the timing of the disengagement of the controlling cam under the action of the counting device.

It is obvious that the shifting of the feed-regulator lever 132 will cause the shifting of the slide-block 125 toward or from the rock-shaft 116, thereby varying the length of the straightaway stitches and the consequent spacing apart of the consecutive tacks. 75

As is common in this class of machines, the presser-bar 238 has fixed thereon a collar 254 formed with a backwardly extending stud 255 projecting above the forward extremity of the treadle-actuated rock-lever 226, and a second lateral stud 256 extending above the presser-lifting cam-lever 257. As will be readily seen, when the treadle-rod 29 is drawn downward to rock the lifting lever 226 for raising the presser-foot, the tack-controlling mechanism will be set for a cycle of operation as before described, but when the presser-foot is manually lifted by operation of the finger-lever 257, such controlling mechanism will 85 be left undisturbed. Provision is thus made in the machine for raising the presser-foot in continuous straightaway stitching and while the controlling cam 57 is inactive, or during a cycle of operation controlled by 90 said cam and without affecting its period of normal operation by actuation of the push-rod 175 with its controlling catch-lever 184 and forked counting-bar disengaging arm 187. 100

While the controlling-cam driving element 97 is shown provided with worm-driven means for turning it continuously in the same direction, it is evident that any other suitable means may be used for imparting thereto a constant movement, that is, a movement during each stitch-forming cycle which may be communicated to the cam 57 in the normal operation of the stitching mechanism. The roller-stud 149 constitutes a normally operative cam-follower which serves to restrict in greater or less degree, in conjunction with the cam-tracks 152 and 153, the maximum work-advancing action of the feeding mechanism, and it is obvious that the mechanism employed to this end may be widely varied within the scope of the present invention. 115

In the present embodiment of the improvement, the pitch of the ratchet-teeth 209 of the rack-bar 193 is preferably proportionate to the throw of the pawl lever arm 215, and the notches or nicks 197 of said bar are preferably spaced proportionately also to the pitch of the ratchet-teeth. 125

Having thus set forth the nature of the invention what I claim herein is:—

1. In a sewing machine, in combination, stitch-forming mechanism including a reciprocating and laterally jogging needle, 130

work-feeding means, cord-presenting means for directing a cord within the range of reciprocation and lateral jogging movement of the needle, and automatically acting controlling means connected with said needle and acting thereon in the production of successive groups of stitches, while the feeding means continue in operation, for imparting to said needle lateral jogging movements followed by intervals of lateral immobility, for production of spaced groups of zigzag stitches penetrating both the cord and the work at the side thereof with the intermediate straightaway stitches at the side of the cord.

2. In a sewing machine, in combination, stitch-forming mechanism including a reciprocating and laterally jogging needle, work-feeding means, cord-presenting means for directing the cord within the range of reciprocation and lateral jogging movement of the needle, and automatically acting controlling means connected with said needle and acting thereon in the production of successive groups of stitches, while the feeding means continue in operation, for imparting to said needle lateral jogging movements followed by intervals of lateral immobility, for production of spaced groups of zigzag stitches penetrating both the cord and the work at both sides thereof with intermediate straightaway stitches at one side of the cord.

3. In a sewing machine, the combination with work-feeding means and a cord-guide having an orifice directed in the line of feed, of stitch-forming mechanism including a laterally movable needle and means for imparting jogging movements thereto of an amplitude exceeding the width of orifice of said cord-guide, and controlling means connected with and actuated by a moving part of the machine and acting at predetermined intervals to change the character of the stitching for production of alternate groups of straightaway and zigzag stitches respectively at the side of and embracing a cord issuing from said guide.

4. In a sewing machine, the combination with cord-guiding and work-feeding means, of stitch-forming mechanism including a reciprocating and laterally jogging needle, and controlling means connected with said needle and acting thereon in the production of successive groups of stitches to alternately impart thereto single-throw and plural-throw lateral jogging movements and thereafter maintain the same laterally immovable, whereby spaced groups of lateral stitches are produced at intervals both embracing and penetrating the cord.

5. In a sewing machine, the combination with cord-guiding and work-feeding means, of stitch-forming mechanism including a laterally jogging needle with means for re-

ciprocating it throughout the period of action of the feeding mechanism, and controlling means connected with said needle and acting thereon in the production of successive groups of stitches to alternately impart thereto single-throw and plural-throw lateral jogging movements and thereafter maintain the same laterally immovable, whereby spaced groups of lateral stitches are produced at intervals both embracing and penetrating the cord with intermediate lines of straightaway stitches at one side of the cord.

6. In a sewing machine, the combination with cord-guiding and work-feeding means, of stitch-forming mechanism, controlling means therefor adapted to periodically vary the character of the stitching for successive production of groups of straightaway and zigzag stitches, and automatic controlling means acting intermediate the initial and final stitch-forming cycles of a zigzag stitching period for varying the length of feed during the production of the zigzag stitches of each group of each of said groups of zigzag stitches.

7. In a sewing machine, the combination with cord-guiding and work-feeding means, of stitch-forming mechanism, controlling means therefor adapted to periodically vary the character of the stitching for successive production of groups of straightaway and zigzag stitches, and automatic controlling means for the work-feeding means and including an adjustable element and actuating means therefor acting intermediate the initial and final stitch-forming cycles of a zigzag stitching period whereby the rate of advance of the work between successions of initial and final zigzag stitches of each group may be determined.

8. In a sewing machine, the combination with work-feeding mechanism, and stitch-forming mechanism, of controlling means for the stitch-forming mechanism for alternate production of straightaway and zigzag stitches, and controlling means for the work-feeding mechanism including a cam having a plurality of independently and successively operative portions whereby the work is advanced at different rates of speed for each of two spaced groups of zigzag stitches and an intermediate group of straightaway stitches.

9. In a sewing machine, in combination, stitch-forming mechanism, controlling means for the stitch-forming mechanism for alternate production of straightaway and zigzag stitches, feeding mechanism including a work-engaging member, an element connected with said work-engaging member, a plurality of mutually independent actuating means for said element, and automatic controlling means for rendering said actuating means effective successively.

10. In a sewing machine, the combination with stitch-forming and feeding mechanisms, and controlling means acting automatically throughout a period including a plurality of stitch-forming cycles and connected with the stitch-forming mechanism to effect the production of alternate groups of tacking and straightaway stitching, of means connected with and actuated by a moving part of the machine for rendering said controlling means inactive at the end of said period and while the stitch-forming and feeding mechanisms continue in operation. 16
11. In a sewing machine, the combination with stitch-forming and feeding mechanisms, and controlling means acting automatically throughout a period including a plurality of stitch-forming cycles and connected with the stitch-forming mechanism to effect the production of alternate groups of tacking and straightaway stitching, of means connected with and actuated by a moving part of the machine and including an adjusting device for determining its time of action for rendering said controlling means inactive at the end of said period and while the stitch-forming and feeding mechanisms continue in operation. 25
12. In a sewing machine, the combination with stitch-forming and feeding mechanisms, of a controlling cam operatively connected with the stitch-forming mechanism whereby alternate groups of straightaway and tacking stitches are produced, actuating means for said cam, and means operatively connected with a moving part of the machine for disconnecting said cam from its actuating means while the stitch-forming and feeding mechanisms continue in operation. 39
13. In a sewing machine, the combination with stitch-forming and feeding mechanisms, of a controlling cam operatively connected with the stitch-forming mechanism whereby alternate groups of straightaway and tacking stitches are produced, actuating means for said cam, means for disconnecting said cam from its actuating means while the stitch-forming and feeding mechanisms continue in operation, and adjustable means for timing the action of said disconnecting means. 59
14. In a sewing machine, the combination with work-feeding mechanism, and stitch-forming mechanism, of controlling means for the stitch-forming mechanism for alternate production of straightaway and zigzag stitches, controlling means for the work-feeding mechanism whereby the work is normally advanced at different rates of speed for each of two spaced groups of zigzag stitches and an intermediate group of straightaway stitches, and means connected with said controlling means whereby the spacing of the stitches of a succeeding group of zigzag stitches may be made to conform with that of an initial group. 65
15. In a sewing machine, the combination with work-feeding mechanism, and stitch-forming mechanism, of controlling means for the stitch-forming mechanism for alternate production of straightaway and zigzag stitches, controlling means for the work-feeding mechanism whereby the work is normally advanced at different rates of speed for each of two spaced groups of zigzag stitches and an intermediate group of straightaway stitches, and means connected with said controlling means and under the control of the operator whereby the spacing of the stitches of a succeeding group of zigzag stitches may be made to conform with that of an initial group. 75
16. In a sewing machine, the combination with stitch-forming mechanism, of means operatively connected with and adapted to control said stitch forming mechanism for alternate production of straight-away and zigzag stitches, feeding mechanism comprising a feed-dog, means for normally actuating said feeding mechanism, and means operatively connected with a moving part of the machine connected with and adapted to control said feeding mechanism to vary the action of the feed-dog during the production of zigzag stitches. 85
17. In a sewing machine, the combination with work-feeding mechanism comprising a feed-dog, and stitch-forming mechanism, of controlling means connected with the stitch-forming mechanism for alternate production of straight-away and zigzag stitches, means connected with the feeding mechanism for initially maintaining the feed-dog in operative relation with the work during a succession of stitch-forming cycles and moving it progressively in the same direction to advance the work during the production of a group of zigzag stitches, and means for thereafter imparting to the feed-dog a plurality of rising and falling and reciprocatory feeding movements in succeeding groups of straight-away and zigzag stitches. 100
18. In a sewing machine, the combination with stitch-forming mechanism and controlling means operatively connected therewith for alternate production of straight-away and zigzag stitches, of feeding mechanism comprising a feed-dog, feed-lifting and reciprocating cams operatively connected with said feed-dog, and controlling means operatively connected with said feeding mechanism and adapted to render ineffective the feed-reciprocating cam during the production of a predetermined group of zigzag stitches, and means controlled by the machine to act subsequently thereto for varying the effective action of said cam during the 110
19. In a sewing machine, the combination with work-feeding mechanism, and stitch-forming mechanism, of controlling means for the stitch-forming mechanism for alternate production of straightaway and zigzag stitches, controlling means for the work-feeding mechanism whereby the work is normally advanced at different rates of speed for each of two spaced groups of zigzag stitches and an intermediate group of straightaway stitches, and means connected with said controlling means whereby the spacing of the stitches of a succeeding group of zigzag stitches may be made to conform with that of an initial group. 115
20. In a sewing machine, the combination with work-feeding mechanism, and stitch-forming mechanism, of controlling means for the stitch-forming mechanism for alternate production of straightaway and zigzag stitches, controlling means for the work-feeding mechanism whereby the work is normally advanced at different rates of speed for each of two spaced groups of zigzag stitches and an intermediate group of straightaway stitches, and means connected with said controlling means and under the control of the operator whereby the spacing of the stitches of a succeeding group of zigzag stitches may be made to conform with that of an initial group. 120
21. In a sewing machine, the combination with work-feeding mechanism, and stitch-forming mechanism, of controlling means for the stitch-forming mechanism for alternate production of straightaway and zigzag stitches, controlling means for the work-feeding mechanism whereby the work is normally advanced at different rates of speed for each of two spaced groups of zigzag stitches and an intermediate group of straightaway stitches, and means connected with said controlling means whereby the spacing of the stitches of a succeeding group of zigzag stitches may be made to conform with that of an initial group. 125
22. In a sewing machine, the combination with work-feeding mechanism, and stitch-forming mechanism, of controlling means for the stitch-forming mechanism for alternate production of straightaway and zigzag stitches, controlling means for the work-feeding mechanism whereby the work is normally advanced at different rates of speed for each of two spaced groups of zigzag stitches and an intermediate group of straightaway stitches, and means connected with said controlling means and under the control of the operator whereby the spacing of the stitches of a succeeding group of zigzag stitches may be made to conform with that of an initial group. 130

- production of successive groups of zigzag stitches.
19. In a sewing machine, in combination with stitch-forming mechanism, of a controlling cam operatively connected with the stitch-forming mechanism whereby alternate groups of straight-away and zigzag stitches are produced, of feeding mechanism comprising a feed-dog, feed-lifting and reciprocating cams and spring-pressed members connected with the feed-dog and normally maintained within the range of action of said cams, of a stop member adapted to be thrown into engagement with the feed-dog 15 to maintain the same lifted during the production of a predetermined group of zigzag stitches, and controlling means for said feeding mechanism adapted to impart to the feed-dog a progressive forward movement 20 during the formation of said group of stitches, and to render ineffective the action of the feed-reciprocating cam during such movement.
20. In a sewing machine, the combination 25 with stitch-forming and feeding mechanism, of controlling means connected with the stitch-forming mechanism to effect the production of alternate groups of straight-away and zigzag stitches, feed controlling means comprising a movable cam-member provided 30 with a plurality of operative portions, and a spring-pressed follower adapted for successive engagement with said operative portions of the cam and having a connection 35 with said feeding mechanism whereby the action of the latter is varied during the production of zigzag stitches.
21. In a sewing machine, the combination 40 with stitch-forming and feeding mechanism, of controlling means connected with the stitch-forming mechanism to effect the production of alternate groups of straight-away and zigzag stitches, feed controlling means comprising a rotary cam formed with a track 45 having relatively adjustable operative portions, and a spring-pressed follower having a connection with said feeding mechanism and adapted for successive engagement with the operative portions of said cam, whereby 50 the action of the feeding mechanism is varied during the production of zigzag stitches.
22. In a sewing machine, the combination 55 with stitch-forming mechanism including a reciprocating and laterally jogging needle, and needle-jogging means, of a rotary controlling cam adapted for operative connection with said needle-jogging means, a constantly moving driving element therefor, 60 and means for coupling said controlling cam with its driving element for rotation in unison with the latter.
23. In a sewing machine, the combination 65 with stitch-forming mechanism including a reciprocating and laterally jogging needle, and needle-jogging means, of a rotary controlling cam adapted for operative connection with said needle-jogging means, a constantly moving driving element therefor, and means for coupling said controlling cam with its driving element for rotation in unison with the latter.
24. In a sewing machine, the combination 75 with stitch-forming mechanism including a reciprocating and laterally jogging needle, needle-jogging means, and feeding mechanism, of a rotary controlling cam adapted for operative connection with said needle-jogging means and feeding mechanism, a constantly moving driving element therefor, and means for temporarily coupling said controlling cam with its driving element for rotation in unison with the latter.
25. In a sewing machine, the combination 80 with stitch-forming and feeding mechanisms, of a rotary controlling cam operatively connected with said mechanisms, a constantly moving driving element for said cam, a coupling element carried by one of said parts and adapted to couple it with the other, and operating means for said coupling element including oppositely acting springs of different strength and means for applying and 85 relieving the pressure upon the stronger of said springs for imparting coupling and uncoupling movements to said coupling element.
26. In a sewing machine, the combination 90 with stitch-forming and feeding mechanisms, of a rotary controlling cam operatively connected with said mechanisms, a constantly moving driving element therefor, a spring-retracted coupling element carried 95 by one of said parts, and adapted to couple it with the other, and a spring-pressed actuator adapted for throwing said coupling element into operative position.
27. In a sewing machine, the combination 100 with stitch-forming and feeding mechanisms, of a rotary controlling cam operatively connected with said mechanisms, a constantly moving driving element therefor, a spring-retracted coupling element carried 105 by one of said parts, and adapted to couple it with the other, and a spring-pressed actuator adapted for throwing said coupling element into operative position.
28. In a sewing machine, the combination 110 with stitch-forming and feeding mechanisms, of a rotary controlling cam operatively connected with said mechanisms, a constantly moving driving element therefor, a coupling element for connecting said parts, 115 a shouldered coupler-rod for shifting the coupling element, a spring applied to said rod for moving it in one direction, an oscillatory spring-pressed push-rod, an arm carried by said rod and adapted for engagement with the shoulder of said coupler-rod, and means for shifting endwise and turning said push-rod in opposition to its spring.
29. In a sewing machine, the combination 120 with stitch-forming and feeding mechanisms, of a rotary controlling cam operatively connected with said mechanisms, a constantly moving driving element therefor, a coupling element for connecting said parts, 125 a shouldered coupler-rod for shifting the

coupling element, a spring applied to said rod for moving it in one direction, an oscillatory push-rod, an arm carried by said rod and adapted for engagement with the shoulder of said coupler-rod, a spring acting upon said push-rod in opposition to that of the coupler-rod and adapted to turn said arm into engagement with the coupler-rod, means for depressing the push-rod for engagement of its arm with the coupler-rod, and automatically acting means for disengagement of said arm from the coupler-rod.

29. In a sewing machine, the combination with stitch-forming and feeding mechanisms, of a rotary controlling cam adapted for operative connection with said stitch-forming and feeding mechanisms for periodically changing the character of the stitching and varying the feeding movements, a constantly moving driving element, coupling means for connecting said cam with the driving element, and automatically acting means connected with said coupling means for disconnecting said cam from the driving element 25 while the stitch-forming and feeding mechanisms continue in operation.

30. In a sewing machine, the combination with stitch-forming and feeding mechanisms, of a rotary controlling cam adapted for operative connection with said stitch-forming and feeding mechanisms for periodically changing the character of the stitching and varying the feeding movements, a constantly moving driving element, 35 coupling means for connecting said cam with the driving element, means connected with said coupling means for disconnecting said cam from the driving element while the stitch-forming and feeding mechanisms continue in operation, and means acting at the completion of a plurality of consecutive rotations of said cam for throwing said disconnecting means into action.

31. In a sewing machine, the combination with stitch-forming and feeding mechanisms, of a rotary controlling cam adapted for operative connection with said stitch-forming and feeding mechanisms for periodically changing the character of the stitching and varying the feeding movements, a constantly moving driving element, coupling means for connecting said cam with the driving element, means connected with said coupling means for disconnecting said cam from the driving element while the stitch-forming and feeding mechanisms continue in operation, and means adjustable 55 for operation after any number of rotations of said cam within a predetermined maximum for throwing said disconnecting means into action.

32. In a sewing machine, the combination with stitch-forming and feeding mechanisms, of a rotary controlling cam adapted for operative connection with said stitch-

forming and feeding mechanisms for periodically changing the character of the stitching and varying the feeding movements, a constantly moving driving element, coupling means for connecting said cam with the driving element and including a controlling catch-lever for maintaining such connection, a trip-device for said catch-lever, and means connected with said cam for imparting to said trip-device step-by-step operative movements toward said catch-lever.

33. In a sewing machine, the combination with stitch-forming and feeding mechanisms, of a rotary controlling cam adapted for operative connection with said stitch-forming and feeding mechanisms for periodically changing the character of the stitching and varying the feeding movements, a constantly moving driving element, 50 coupling means for connecting said cam with the driving element and including a controlling catch-lever for maintaining such connection, a reciprocatory trip-device for said catch-lever, means connected with said cam for imparting to said trip-device step-by-step operative movements from an initial position, and means for returning said trip-device to initial position after a tripping action.

34. In a sewing machine, the combination with stitch-forming and feeding mechanisms, of a rotary controlling cam operatively connected with said mechanisms, driving means therefor, a coupling device for connecting said cam with its driving device, and means connected with said coupling device for disconnecting said cam and its driving device and comprising a catch-lever, a spring-retracted rack-bar, a pawl-carrying lever, a pawl mounted thereon and adapted for engagement with said rack-bar, a pawl-actuating cam rotating with said controlling cam for vibrating the pawl-carrying lever, a trip-rod mounted upon said rack-bar and adapted for engagement with said catch-lever, and means for disengaging said pawl from the rack-bar.

35. In a sewing machine, the combination with stitch-forming and feeding mechanisms, of a rotary controlling cam operatively connected with said mechanisms, driving means therefor, a coupling device for connecting said cam with its driving device, and means connected with said coupling device for disconnecting said cam and its driving device and comprising a catch-lever, a spring-retracted rack-bar formed with a series of notches spaced apart proportionately with the pitch of its teeth, a pawl-carrying lever, a pawl mounted thereon and adapted for engagement with said rack-bar, a pawl-actuating cam rotating with said controlling cam for vibrating the pawl-carrying lever an adjustable collar mounted upon said

rack-bar and provided with a spring-pressed latch-tooth adapted to enter one of the notches of the rack-bar, a trip-rod sustained by said collar and adapted for engagement with said catch-lever, and means for disengaging said pawl from the rack-bar.

36. In a sewing machine, the combination with stitch-forming and feeding mechanisms, a presser-foot, and lifting means therefor, of a rotary controlling cam operatively connected with said stitch-forming and feeding mechanisms, a constantly moving driving element therefor, a coupling device for temporarily connecting said cam with the driving element, means acting upon said coupling device and controlled by the rotation of said cam for disconnecting the latter from its driving element after a plurality of consecutive rotations thereof, and means controlled by the lifting of the presser-foot for reestablishing through said coupling device operative relation between said driving element and cam.

37. In a sewing machine, the combination with stitch-forming and feeding mechanisms, a presser-foot, and lifting means therefor, of a rotary controlling cam operatively connected with said stitch-forming and feeding mechanisms, a constantly moving driving element therefor, a coupling device for temporarily connecting said cam with the driving element, means acting upon said coupling device and controlled by the rotation of said cam for disconnecting the latter from its driving element after a plurality of consecutive rotations thereof, means controlled by the lifting of the presser-foot for reestablishing through said coupling device operative relation between said driving element and cam, and means independent of said presser-foot lifting means whereby the presser-foot may be lifted without affecting said coupling device.

38. In a sewing machine, the combination with stitch-forming and feeding mechanisms, of a rotary controlling cam operatively connected with said stitch-forming and feeding mechanisms for periodically changing the character of the stitching and varying the feeding movements, a driving element adapted to impart to said cam a single rotation during a plurality of stitch-forming cycles, a normally inoperative coupling device adapted to operatively connect said cams with its driving element for any one of said plurality of stitch-forming cycles but permitting the manual turning of the cam preparatory to its coupling action for setting the same correspondingly with the desired stitch-forming cycle, and controlling means for said coupling device.

39. In a sewing machine, the combination with stitch-forming mechanism, and work-feeding mechanism, of controlling means for the stitch-forming mechanism for alternate

production of straightaway and zigzag stitches, controlling means for the work-feeding mechanism normally adapted to restrict the action of the feeding mechanism during the production of a succession of zigzag stitches and to permit a more extended range of action for an adjacent succession of straightaway stitches and connected zigzag stitches, and manually controlled means connected with said controlling means for causing a repetition of the restricted feeding action.

40. In a sewing machine, the combination with stitch-forming mechanism, and work-feeding mechanism, of a controlling cam, a connection between said cam and the stitch-forming mechanism for effecting the alternate production of straightaway and zigzag stitches, a connection between said cam and the work-feeding mechanism, means controlled by said cam normally adapted to cause a restricted action of the feeding mechanism during the production of a succession of zigzag stitches and to permit a more extended range of action for an adjacent succession of straightaway stitches and connected zigzag stitches, driving means for said cam, coupling means for connecting the cam with its driving means, automatically acting means connected with said coupling means for disconnecting the cam from its driving means at the completion of a plurality of rotations, manually controlled means for rendering said automatically acting means ineffective, and manually controlled means connected with said controlling means for causing a repetition of the restricted feeding action after an initial restricted feeding action.

41. In a sewing machine, the combination with a tubular needle-bar and means for imparting thereto endwise reciprocating movements, of a plurality of laterally movable needle-holders carried by said needle-bar, needles mounted in said holders, a rod journaled within and reciprocating with said needle-bar, means for oscillating said rod, and a positive connection between said rod and said needle-holders for imparting to the needles simultaneous lateral jogging movements of equal amplitude.

42. In a sewing machine, the combination with a tubular needle-bar and means for imparting thereto endwise reciprocating movements, of a plurality of laterally and independently movable needle-holders carried by said needle-bar, needles mounted in said holders, a rod journaled within and reciprocating with said needle-bar, means for oscillating said rod, and crank-and-pitman connections between said rod and needle-holders.

43. In a sewing machine, the combination with a tubular needle-bar and means for im-

parting thereto endwise reciprocating movements, of a plurality of laterally movable needle-holders carried by said needle-bar, needles mounted in said holders, a rod journaled within and reciprocating with said needle-bar, a rocking bracket journaled concentrically with the needle-bar and having a spline-and-groove connection with said rod, means for rocking said bracket, and an operative connection for imparting to the needles simultaneous lateral jogging movements of equal amplitude.

44. In a sewing machine, the combination with two reciprocating needles adapted for relative lateral movement, loop-takers circularly movable upon different axes and adapted to coöperate with the respective needles, and actuating means for imparting operative loop-seizing movements to said loop-takers, of loop-taker supports movable each toward and from the other and transversely of the axis of movement of its respective loop-taker, and means connected with each of said needles and the support for its co-operating loop-taker for producing simultaneous lateral movements of said needles and their respective loop-takers toward and from the other needle and loop-taker.

45. In a sewing machine, the combination with two reciprocating and laterally movable needles, loop-takers coöoperating with the respective needles, and means for imparting operative loop-seizing movements to said loop-takers, of laterally and relatively movable supports upon which said loop-takers are mounted, a rocking frame, a cam for imparting operative movements thereto, connections between said rocking frame and the needles for imparting to the latter simultaneous lateral jogging movements toward and from each other, and connections between said rocking frame and the loop-taker supports for imparting to the latter simultaneous jogging movements toward and from each other corresponding in amplitude with those of the needles.

46. In a sewing machine, the combination with two reciprocating and laterally movable needles, loop-takers coöoperating with the respective needles, and means for imparting operative loop-seizing movements to said loop-takers, of laterally and relatively movable supports upon which said loop-takers are mounted, a rocking frame, a cam formed with active and inactive portions and adapted to impart to said rocking frame a series of rocking movements followed by a period of inaction, connections between said rocking frame and the needles for imparting to the latter simultaneous lateral jogging movements toward and from each other, and connections between said rocking frame and the loop-taker supports for imparting to the latter simultaneous jogging movements toward and from each

other corresponding in amplitude with those of the needles.

47. In a sewing machine, the combination with work-feeding means, and cord-guiding means comprising a presser-foot formed with laterally spaced cord-guiding channels and provided with a depending cord-loop detaining member, of stitch-forming mechanism including a reciprocating and laterally jogging needle, and controlling means connected with said needle and acting thereon in the production of successive groups of stitches to alternately impart thereto lateral jogging movements and thereafter maintain the same laterally immovable, whereby spaced groups of lateral stitches are produced which embrace the cord.

48. In a sewing machine, the combination with a work-feeding means, and cord-guiding means comprising a presser-foot formed with needle apertures and laterally spaced cord receiving channels leading to said apertures and provided with a cord-loop detaining spur projecting from its lower face, of stitch-forming mechanism including a reciprocating and laterally jogging needle, and controlling means connected with said needle and acting thereon in the production of successive groups of stitches to alternately impart thereto lateral jogging movements and thereafter maintain the same laterally immovable, whereby spaced groups of lateral stitches are produced which embrace the cord.

49. In a sewing machine, the combination with cord-guiding means, of stitch-forming and feeding mechanisms adapted for successive production of series of straightaway stitches and intermediate series of zigzag stitches of different depths, and controlling means operative at intervals embracing a plurality of stitch-forming cycles and connected with the stitch-forming mechanism for effecting changes between straightaway and zigzag stitching and including a normally inactive operative element with means connected with and adapted to impart to said element movements of consecutively different amplitude.

50. In a sewing machine, the combination with work-feeding means and a cord-guide having an orifice directed in the line of feed, of stitch-forming mechanism, means for producing relative jogging movements between the stitch-forming mechanism and said cord-guide, and controlling means connected with the jogging means and actuated by a connection with a moving part of the machine for effecting the interruption of the action of said jogging means for periods of predetermined length and each including a plurality of stitch-forming cycles.

51. In a sewing machine, the combination with overseaming stitch-forming and feeding mechanisms adapted for successive pro-

duction of series of straightaway stitches and intermediate series of overseam stitches of a cord-guide having an orifice narrower than the range of movement of the stitch-forming mechanism when producing overseam stitches and directed in the line of feed, and controlling means intermediate the stitch-forming mechanism and a moving part of the machine and acting automatically at intervals of predetermined length for effecting changes between the straightaway and overseam stitching, whereby a cord may be bound to a body fabric by spaced groups of overseam stitches connected by lines of straightaway stitches at the side and beyond the edge of the cord.

52. In a sewing machine, in combination, stitch-forming mechanism, controlling means for the stitch-forming mechanism for alternate production of straightaway and zigzag stitches, feeding mechanism including a work-engaging member, an element connect-

ed with said work-engaging member, three independently acting actuating means for said element, and controlling means for rendering said actuating means effective in a fixed order of succession. 25

53. In a sewing machine, the combination with stitch-forming mechanism, of controlling means therefor for alternate production of straightaway and zigzag stitches, work-feeding mechanism, a plurality of mutually independently operable actuating means therefor, and automatic controlling means for said actuating means operating to render them effective in a fixed order of succession. 30 35

In testimony whereof, I have signed my name to this specification, in the presence of two subscribing witnesses.

ALBERT H. DE VOE.

Witnesses:

W. P. STEWAERT,
H. A. KORNEMANN, Jr.

Copies of this patent may be obtained for five cents each, by addressing the "Commissioner of Patents, Washington, D. C."

It is hereby certified that in Letters Patent No. 1,164,789, granted December 21, 1915, upon the application of Albert H. De Voe, of Westfield, New Jersey, for an improvement in "Tacking and Stitching Machines," errors appear in the printed specification requiring correction as follows: Page 4, strike out line 76 and insert the words and numeral *hus 162 and a bearing member of the bed-*; page 8, lines 89-90, claim 6, strike out the words "of the zigzag stitches of each group"; and that the said Letters Patent should be read with these corrections therein that the same may conform to the record of the case in the Patent Office.

Signed and sealed this 21st day of March, A. D., 1916.

[SEAL.]

J. T. NEWTON,

Acting Commissioner of Patents.
